UNITED STATES PATENT OFFICE.

WILLIAM B. FENN, OF WINFIELD, NEW YORK, ASSIGNEE TO EZRA D. BECKWITH, OF SAME PLACE.

DESIGN FOR A WATER-BOTTLE.

SPECIFICATION forming part of Design No. 32,426, dated April 3, 1900.

Application filed March 7, 1900. Serial No. 7,727. Term of patent 31 years.

To all whom it may concern:

Be it known that I, WILLIAM B. FENN, a citizen of the United States, residing at West Winfield, in the county of Herkimer and State of New York, have invented and produced a new and original Design for Water-Bottles; and I do hereby declare the following to be a full, clear, and exact description of the same, reference being had to the accompanying drawing, forming part thereof, and in which the figure is a side elevation of a water-bottle embodying my design.

A represents the body or base of the bottle and which is substantially spherical in shape.

B represents the neck, which extends vertically from the upper central portion of the base of the bottle and is provided with a lower outwardly-flaring surface B'. Extending from said flaring surface is a ring C, having an upper tapering surface C' and a vertical lower

surface C², which joins the upper surface of the spherical base. Arranged circumferentially on the said tapering and vertical surfaces of the ring are annular rows of beads D.

The essential features of my design consist in the spherical base, the vertical neck extending from the upper central portion of the base, said neck having a lower outwardly-flaring portion, and a ring having an upper inwardly-directed portion which joins the said flaring portion and a lower downwardly-directed portion which joins the upper portion of the base.

I claim as my invention—

The design for a bottle, substantially as herein shown and described.

WILLIAM B. FENN.
